(57) **CLAIM**

The ornamental design for a surface configuration of a seat for a vehicle, as shown and described.

DESCRIPTION

FIG. 1 is a left front perspective view of a surface configuration of a seat for a vehicle according to our design, the right front perspective view being mirror image; and,

FIG. 2 is a left side perspective view of the surface configuration of a seat for a vehicle according to our novel design, the right side perspective view being mirror image. The dash lines included depict environment and are not part of the claimed design.
